UNITED STATES PATENT OFFICE.

NATHAN SANDALS, OF JERSEY CITY, NEW JERSEY.

CHIROPRACTIC SANITARY PAPER CONTAINER.

1,416,882.

Specification of Letters Patent. Patented May 23, 1922.

Application filed June 26, 1920. Serial No. 391,958.

To all whom it may concern:

Be it known that I, NATHAN SANDALS, a citizen of the United States, residing at Jersey City, county of Hudson, and State 5 of New Jersey, have invented certain new and useful Improvements in Chiropractic Sanitary Paper Containers, of which the following is a specification.

This invention relates generally to toilet fixtures, having more particular reference 10 to a paper container adapted to hold a roll of paper which is fed therefrom as desired, the invention being suitable for use in connection with toilet seats, head rests for 15 barber chairs or other devices.

The invention has for an object to provide 20 a simple and inexpensive paper container which may be suitably mounted where desired, and which has co-operating therewith a means for holding a projecting length of paper drawn from the container proper and severing the soiled or used lengths from the main roll.

For further comprehension of the invention, and of the objects and advantages 25 thereof, reference will be had to the following description and accompanying drawings, and to the appended claims in which the various novel features of the invention are more particularly set forth.

Fig. 1 of the drawings is a plan view 30 of a device constructed according to my invention.

Fig. 2 is a transverse section on the line 35 2—2 of Fig. 1.

Fig. 3 is a detail horizontal section on the line 3—3 of Fig. 2, and

Fig. 4 is an end view.

In the drawings I have shown my improved device as mounted on a support 1 and it is to be understood that this may be 40 any desired part or support such as a toilet seat or the head rest of a barber's chair. My improved container preferably comprises a cylindrical box 2 which may be flattened along one side as at 2' and provided with convexed or semi-spherical ends or heads 3. Secured to this flattened side 2', by riveting or otherwise, is a bar or strap 4 which 45 projects at its ends beyond the ends of the cylinder, these projecting ends being provided with suitable apertures to receive screws 5 whereby the bar 4, and with it the cylinder 2, is mounted on the support 1, 50 being here shown positioned with the bar

extending along one edge of the support as shown.

The upper side of this cylinder is formed by a hinged cover section 7 which is hinged to the main body of the cylinder as at 8 on 60 the side thereof opposite the bar. The free edge of the cover section 7 and the adjacent edge of the main body of the cylinder are provided with curved spring members 9 and 10 which are adapted to snap into engagement to resiliently hold the cover closed. The latter may be provided with a knob or handle 11 whereby it may be grasped to be 65 swung back. Formed in the cover section 7, and extending substantially from end to 70 end of the cylinder a short distance above the free edge of the cover section is a slot 12 through which the roll of paper is fed from the cylinder, the roll of paper being indicated at 13 within the cylinder, a portion 75 of the paper being shown at 13' as withdrawn through the slot 12 and extending over the support 1, the cylinder being preferably mounted on the latter to have the slot 12 in horizontal alinement with the 80 top of the support.

The roll of paper may be conveniently mounted on a wooden rod or mandrel 15 which is rotatably supported at opposite ends in the ends 3 of the cylinder. As here 85 shown one end of the mandrel 15 is diminished as at 16 and engages in a complementary opening in the adjacent cylinder end, while the opposite end of the mandrel is supported by a pin 17 which engages freely 90 in a suitable socket in the end of the mandrel. This pin projects from a screw cap 18 which is screwed into an opening in the cylinder end, this opening being of sufficient size to permit of insertion of the 95 mandrel.

Upon the opposite edge of the support 1 to that carrying the container just described I preferably mount a device for holding the sheet flat upon the support and for facilitating the severing of the used portions. To this end a shelf 20 extends flush with the top of the support, being secured to the latter by means of an integral angular flange 21 which extends along the edge of 105 the support and is fastened thereto by screws 22.

Upon this shelf is mounted a device adapted to bear resiliently upon the paper 13' this device consisting of an angular bar having 110

a vertical flange 23 which extends into close proximity to the paper, and a forwardly and downwardly inclined flange 24. This bar is pivotally mounted on the shelf 20, 5 being fixed on a rod 25 which extends therealong in the apex of the two flanges and is journaled at its ends in lugs 26 on the shelf. The flange 24 is pressed against the paper by means of a pair of tension springs 27 10 located at opposite ends of the flange and connected respectively at opposite ends to the shelf 20 and to this flange 24. A knob 28 is provided on the bar to permit of its being swung clear of the paper when it is 15 desired to pull the paper forward, the front edge of the shelf being preferably sharpened to a knife edge so as to permit of easy severing of the used end of the paper by pressing it downwardly over this knife edge.

20 Having thus described my invention what I claim as new and desire to protect by Letters Patent of the United States is as follows:

1. In a device of the character described, 25 the combination with a support comprising a cylindrical box, the top wall of which is formed by a hinged cover section, said cover section being longitudinally slotted in alignment with the upper surface of said support, and means for supporting a roll of 30 paper in the container, said means including a mandrel having a reduced end engaging

in an opening in one end of the cylindrical box, the opposite end of said mandrel being formed with a socket, a screw threaded 35 into an aperture in the adjacent end of the cylindrical box, and a pin on said screw projecting into the said socket, said last mentioned opening being large enough to permit of insertion of the mandrel therethrough. 40

2. A sanitary paper container and support comprising a supporting member having a spacing bar on one longitudinal edge, a housing carried by said spacing bar, a cover for said housing, said cover being provided with a longitudinal slot substantially 45 in alignment with the upper face of the supporting member, means for clamping said cover in closed position, a paper roll supporting member adapted to be inserted 50 and removed from one end of said housing, a closure member for said end of the housing carrying a support for one end of the paper roll carrying member, a shelf secured upon the opposite longitudinal edge of said supporting member to receive paper drawn through the slot of the housing and across 55 said supporting member, and means for resiliently retaining the paper upon the supporting shelf.

60 In testimony whereof I have affixed my signature.

NATHAN SANDALS.
